UNITED STATES PATENT OFFICE

2,013,490

VEHICLE OPERATED DOOR MECHANISM

Nicholas Demosthenes, Savannah, Ga.

Application October 20, 1934, Serial No. 749,301

3 Claims. (Cl. 268—35)

This invention relates to vehicle operated door mechanism.

One of the objects of the invention is to provide for automatically opening and closing vertically swinging doors or gates by utilizing the approaching vehicle to perform all of the operations necessary.

Another feature of the invention is the provision of all operating parts substantially submerged below the level of the closures so as not to interfere with the use of the building.

Further objects of the invention are to provide a device of the character referred to that is strong, compact and durable, having very few parts that need repair, that is very easily installed in any building, that is comparatively inexpensive to manufacture, and that is thoroughly reliable for its intended purpose.

With the foregoing and other objects in view, this invention consists of a novel combination, arrangement and construction of parts that will be hereinafter more specifically described and illustrated in the accompanying drawings and specification, wherein for the purpose of illustration is shown the preferred embodiment of the invention, but it is to be understood that changes, variations, and modifications may be resorted to without departing from the spirit of the invention in the claims hereunto appended.

In the drawings, wherein like reference characters denote corresponding parts throughout the several views:—

Figure 1 is a perspective view of a building illustrating an adaptation of the present invention therewith,

Figure 2 is a top plan view of the operating mechanism in accordance with the present invention showing the operating platform in skeleton form,

Figure 3 is a detailed vertical section taken substantially on line 3—3 of Figure 2 and looking in the direction of the arrows,

Figure 4 is a detailed vertical section taken substantially on line 4—4 of Figure 2 but reversed end for end,

Figure 5 is a detailed vertical section taken substantially on line 5—5 of Figure 2 and looking in the direction of the arrow,

Figure 6 is a perspective view of the door operating lever,

Figure 7 is a perspective view of the adjustable link connection between the crank shaft and the door operating lever, and

Figure 8 is an enlarged fragmentary elevation

of the joint between the rocker arm and the latch bolt.

Referring to the drawings in detail, 10 indicates a building, in the illustration shown being a garage, and having a pair of outwardly swinging doors 11, 12. The doors swing on a vertical axis. In the runway 13 leading to the garage is a substantially cruciform housing A which is submerged in the ground as is clearly illustrated in Figure 2 of the drawings. The top of the housing 10 is flush with the surface of the runway so that the covering in the one case, and the yielding platform in the other case will lie in the path of the vehicle wheels as will hereafter appear.

The longitudinal platform trough of the housing is formed in two sections, 14 indicating the outside section and 15 indicating the section that projects into the building 10 as shown in dotted lines in Figure 1 of the drawings. The part of the housing A indicated at 16 is a transverse trough that is positioned directly in front of the swinging doors 11 and 12 on the outside. The housing A is preferably constructed of wooden boards well creosoted so as to withstand the weather without rotting. There is a yielding platform covering the longitudinal trough formed in two sections, the outer platform section being indicated at 17 and the inner platform section being indicated at 18 and the inner section 18 is of less length than the outer section 17. Where the transverse trough 16 joins the longitudinal trough the platform sections are separated and at this point they are joined by a hinge 19 secured to the under faces of the platform. The hinge 19 is formed with interlocking sleeves that form the bearing 20 for the operating shaft as will hereafter appear. Outer platform section 17 is yieldingly supported upon a coil spring 21 near the outer end, which coil spring is supported vertically in the trough 14.

Adjacent the inner end platform section 17 is supported on another coil spring 22 similar in every respect to the coil spring 21. The inner platform section 18 is supported on a vertically disposed coil spring 23 and all the coil springs are of the same height so as to support the sections of the platform in alignment when not depressed by the weight of a vehicle. Adjacent the outer end platform section 17 is straddled by a substantially U-shaped treadle the bight portion 24 of which is sunk in a cavity in the platform. One leg 25 of the treadle is formed with elongated slot 26 that rides up and down on a keeper stud 27. The other leg 28 of the treadle extends into the trough and is pivoted as at 29 to a ver-

tically swinging bell crank 30 which is pivoted at the angle at 31 to the sides of the trough. The lower end of bell crank 30 is pivoted as at 32 to the outer end of the long, longitudinally disposed 5 posed latch rod 33. Near the inner end of platform section 18 there is another treadle 34 connected to the bell crank 35 which operates another latch rod 36 and these parts are constructed similarly to the companion parts as described 10 in connection with the outer treadle. Both latch rods 33 and 36 move inwardly when the vehicle wheels press down on the respective treadles.

A latch bolt 37 is mounted for sliding movement in the middle of the transverse trough 16. 15 The latch bolt 37 slides vertically on a pin 38 anchored in the side wall of the trough and the pin rides in a slot between two tongues 39, 40. The tongues when the mechanism is in set position bear against the doors and hold them closed, 20 there being one tongue for each door.

There is a certain amount of play in the latch 37 and to keep it projected a pivoted detent arm 37a is mounted in the trough. On the lower end 25 of latch bolt 37 is a curved flange 41 that engages hook 42a on the outer free end of the latch rocker shaft 42. The inner end of the rocker shaft 42 is formed with a crank portion 43, the center portion of which rotates in a bearing on the upper end of the bridge wall 43a, which bridge wall extends 30 across the juncture of the transverse trough 16 and the sectional longitudinal trough. One end of the crank 43 extends into the longitudinal trough and is pivoted as at 44 to the upper end of a flat arm 45. Flat arm 45 is pivoted adjacent 35 its lower end as at 46 to the side wall of the longitudinal trough. Arm 45 swings on its pivot 46 in a vertical plane, and above the pivot the inner end of latch operating rod 36 is pivotally connected as at 47. The inner end of latch rod 33 is pivoted 40 to the lower free end of arm 45 as at 48. Thus the movement of the rod 33 and 36, whichever one is in action, causes arm 45 to rock thereby imparting movement to latch rocker arm 42 and causes the latch bolt 37 to move clear of the 45 doors. Mounted in the transverse trough 16 are a pair of outwardly swinging door operating levers 50, 51 which when in the set position are substantially parallel with each other and lie in the same plane. The confronting ends of the door 50 operating levers are spaced apart so as to grip the respective doors and swing them outwardly. One of the operating rods 50 is selected for particular illustration in Figure 6. Each operating 55 rod has a straight body portion depending from which is a perpendicular bearing portion 52 and on the end of the bearing portion is an inwardly directed extension 53 formed with an opening 54 to receive the outer end of the connecting link as will soon appear. On the other end of the 60 straight body portion of the operating levers is fastened a substantially U-shaped clamp or clip 55. This clip, one for the end of each lever 50, 51 grips the bottom of the respective doors and moves them outwardly when the platform is 65 depressed.

An operating crank shaft is indicated at B and this crank shaft extends longitudinally of the transverse trough and across the juncture with the longitudinal trough. Operating crank shaft 70 B is formed with a straight portion 56 adjacent one end and another straight portion 57 adjacent the other end. Intermediate the straight portions of the crank shaft there is an integral crank 58 which is journaled in hinge sleeve 20 so 75 that when the platforms are depressed crank

shaft B will rotate. At each end of the crank shaft are inwardly directed diagonal extension arms 59 and 60 the ends of which are connected to the adjustable connecting links 61, 62 respectively and these links are in turn connected on the other ends by the eyes to the extension arms on the outer ends of the operating levers 50, 51.

Each link 61, 62 is formed in the same manner and particularly referring to Figure 7 of the drawings the link 61 will be used in the description. The link 61 has a turn buckle body formed with aligned threaded openings which receive the adjustable bolts 65, 66. The outer ends of the bolts are formed with eyes 67 that join the extensions on crank shaft B and the arms 53 on the door operating levers as will be understood by referring to Figure 2 of the drawings.

There is one bearing 68 attached to the inner wall of the transverse trough 16 in which are journaled the bearing portions of operating lever 50, 20 while there is a similar bearing 69 for the operating lever 51. Crank shaft B has three bearings, one of the bearings being indicated at 70 mounted on the bearing wall 71 that extends across the transverse trough 16. Adjacent the 25 crank 58 of the crank shaft B are a pair of bearings 72, 73, the former being mounted on the top of the bridge wall 43a and the latter mounted on the top of the opposed bridge wall 74.

It will be apparent that the crank shaft B 30 lies wholly within the transverse trough 16. Bearing portions of the operating levers 50, 51 are also confined within the transverse trough 16 and lie parallel with the crank shaft B when the mechanism is in set position.

When a vehicle approaching the building 10 on the driveway 13 strikes the outer treadle the latch bolt 37 is released by the rod 33 and rocker arm 42, the latch bolt being moved free of the doors by rocker arm 42. As the weight of the 40 car bears on the outer platform section 17 this platform is depressed thereby rotating the crank shaft B which in turn swings the operating levers 50, 51 and these latter levers being attached to the doors swing them open. When the vehicle 45 is stored within the building 10 free of the inner platform section 18 the springs 21, 22 operate crank shaft B and the operating levers 50, 51 will return the doors to closed position. The treadle is so arranged that it does not operate to move 50 the latch bolt 37 until the doors are in substantially closed position.

When it is desired to take the vehicle from building 10, the car is backed onto the inner platform section 18 where latch bolt 37 is again 55 depressed and inner platform section 18 imparts motion to crank shaft B and swings operating levers 50, 51, outwardly thereby opening the doors. When the weight of the car is free of the platform the doors will return to closed position by the action of the springs 21, 22 and 23.

Having thus described the invention, what is claimed as new is:

1. The combination with a pair of closures 65 swinging on a vertical axis of a jointed yielding platform having a part on each side of the doors and operated by the weight of approaching vehicles, said platform arranged in the path of the vehicle wheels and below the doors, a vertically sliding latch bolt, a latch rocker shaft, a latch treadle on each end of the platform, latch rods connecting the treadles with the rocker shaft for moving the latter when the vehicle wheel strikes the treadle, an operating crank shaft connected with the platform, a pair of 70 75

operating levers connected one with each door, connecting links joining the crank shaft with the door operating levers, said crank shaft formed with a crank intermediate its ends, said 5 crank of the crank shaft journalled to the joint of the platform.

2. The combination with a pair of closures swinging on a vertical axis of a jointed yielding platform having a part on each side of the doors 10 and operated by the weight of approaching vehicles, said platform arranged in the path of the vehicle wheels and below the doors, a vertically sliding latch bolt, a latch rocker shaft, a latch treadle on each end of the platform, latch rods 15 connecting the treadles with the rocker shaft for moving the latter when the vehicle wheel strikes the treadle, an operating crank shaft connected with the platform, a pair of operating levers connected one with each door, connecting 20 links joining the crank shaft with the door operating levers, said crank shaft formed with a crank intermediate its ends, said crank of the crank shaft journalled to the joint of the platform, said connecting links being adjustable so 25 as to insure proper fitting in the doors.

3. The combination with a pair of closures swinging on a vertical axis of a jointed yielding platform having a part on each side of the doors and operated by the weight of approaching vehicles, said platform arranged in the path of the vehicle wheels, and below the doors, a vertically 5 sliding latch bolt, a latch rocker shaft, a latch treadle on each end of the platform, latch rods connecting the treadles with the rocker shaft for moving the latter when the vehicle wheel strikes the treadle, an operating crank shaft connected with the platform, a pair of operating levers connected one with each door, connecting links joining the crank shaft with the door operating levers, said crank shaft formed with a crank intermediate its ends, said 10 crank of the crank shaft journalled to the joint of the platform, said connecting links being adjustable so as to insure proper fitting in the doors, and said crank shaft arranged at right 15 angles to the path of the vehicle and formed with inward extensions on the outer ends thereof. 20

NICHOLAS DEMOSTHENES.
